EXCAVATING APPARATUS

Raymond S. Weimer, Morris, Ill.; Mabel Weimer
administratrix of said Raymond S. Weimer, deceased

Application September 23, 1941, Serial No. 412,011

7 Claims. (Cl. 37—135)

This invention relates to improvements in excavating apparatus.

One object of the invention is to provide an improved drag line bucket for drag line equipment provided with means whereby as the bucket moves to load discharging position, the adjacent connected portions of the haul lines are moved out of the path of movement of the teeth and other forward portions of the bucket whereby wear on the haul lines and associated parts is lessened and impedance with the dumping action of the bucket is avoided.

An additional object of the invention is to provide a bucket which preferably is supported by the hoist line on a pivotal axis adjacent the center of gravity of the empty bucket and which is provided with haul line attaching means which are movable to positions relative to the bucket, upon release of tension on the haul lines, to effect a shifting of the center of gravity of the loaded bucket to facilitate movement of the bucket to load discharging position.

Another object of the invention is to provide in a rearwardly dumping drag line bucket which discharges the load over the rear wall thereof an arrangement whereby the bucket can be rotated about its pivotal axis to the opposite pendent position to enable the bucket to be dropped or lowered with the teeth foremost to cause the latter to penetrate the material being excavated.

An additional object of the invention is to provide a bucket having rigid haul line attaching means which are pivotally connected to the forward portions of the bucket on axes so located as to improve the operation and control of the bucket during loading operations as well as during elevation and transportation thereof to load discharging positions.

Other advantages of the invention accrue from the novel features of construction and arrangement of the parts disclosed in the accompanying drawing wherein,

Figure 1 is a top plan view of a drag line bucket embodying the present improvements;

Figure 2 is a front elevation thereof;

Figure 3 is a side elevation illustrating the bucket in load discharging position;

Figure 4 is a side elevation illustrating the bucket hanging pendent from the hoist line with the teeth directed downwardly;

Figure 5 is a fragmentary side elevation of an improved bucket disposed in a horizontal plane, and

Figure 6 is a side view of an improved bucket loaded and in an elevated position.

In the drawing, the bucket illustrated is a rearwardly dumping bucket and is provided with a bottom 10 having a forward cutting edge which may be in the form of conventional teeth 11. The bucket is shown as being provided with flaring side walls 12 and a flaring rear wall 13 over which the load is discharged when the bucket tilts or rotates to the load discharging position shown in Figure 3. The bucket is provided with hoist line attaching members 14 illustrated as of eye shape to which hoist line branches 15 are attached. These branches are shown attached at their upper ends to a member 16 to which a hoist cable 17 is secured. As will be understood, the hoist cable passes over a sheave at the forward end of the boom and thence passes to the power mechanism of the drag line apparatus. At the forward ends of the side walls 12, haul line attaching members 18 are provided which in the form shown are of clevis like construction and are secured to the bucket side walls by pivot pins 19. Haul line branches 20 are attached to the forward ends of the members 18 as by means of rings 21, which branches converge at a point forwardly of the bucket as will be understood, and at that point are attached to a drag or haul line which also extends to the power mechanism of drag line equipment.

In the present embodiment of the invention, the members 14 are located at or adjacent the center of gravity of the empty bucket whereby the bucket can tilt about the axis defined by the members 14 to either of the positions illustrated in Figures 3 and 4. The axes of the members 18 do not necessarily lie in the inclined planes defined by the respective walls 12, but are disposed at selected angles for producing certain novel results during use of the bucket, one of which is that rearward tilting action of the bucket during use about the pivotal axis defined by the members 14—14, or about the axis defined by the points of the teeth or other axes, including the axis defined by the forward ends of members 18, swings the members 18 outwardly about their axes 19, that is, laterally of the bucket or away from the longitudinal center line thereof. Conversely, any force which tends to tilt the buck forwardly during use tends to swing the members 18 in the opposite direction, that is, inwardly of the bucket. By means of the arrangement disclosed, the bucket, when loaded normally and elevated as illustrated in Figure 6, tends to tilt rearwardly about its pivotal axis 14—14, but such rearward tilting is restrained by suitable tension applied to the haul line during elevation and transporta-

tion of the load to discharging position. Upon release of tension on the haul line by the operator, the loaded bucket begins to tilt rearwardly about the axis defined by members 14-14 whereupon the members 18-18 begin to swing outwardly or laterally of the bucket and thereby move the adjacent ends of the haul line branches 20 out of the arcuate path of movement of the teeth 11 and other forward portions of the bucket. Not only is unnecessary wear on the parts avoided by the described outward swinging movement of the members 18, but the bucket tilts rearwardly to the load discharging position shown in Figure 3 without the impedance to such movement that results from the engagement of the haul line branches with the teeth in conventional buckets. Inasmuch as the members 18 extend forwardly of the bucket normally, the weight of the same tends to resist rearward tilting action of the bucket, but as the members swing outwardly and rearwardly and downwardly during the dumping action of the bucket toward the position of such members shown in Figure 3, such change of position effects a shifting of the center of gravity of the loaded bucket toward the rear thereof which further facilitates or accelerates the dumping action of the bucket. Conversely, as the members 18 are swung forwardly from the position shown in Figure 3 by tension on the haul line, they shift the center of gravity of the empty bucket in a forward direction and render it tiltable forwardly by the exertion of less force.

As shown in the drawing, stabilizer lines or chains 22 extend from the rings 21 to rings 23 which are interposed in the hoist line branches 15. During the elevation of a loaded bucket as well as during the transportation thereof, as pointed out above, tension is applied to the haul line to prevent the bucket from tilting rearwardly until it has been moved to load discharging position. The stabilizing lines 22 prevent the loaded bucket from being tilted forwardly by the force exerted on the forward end of the bucket by the haul lines while the bucket is being elevated and transported. As the bucket tilts rearwardly during the load discharging action, the outward swinging movement of the members 18 also causes the lines 22 to be drawn away from the discharging material to the exterior of the bucket as indicated in Figure 3.

When the bucket has moved to the load discharging position shown in Figure 3 and the load thereby discharged, tension may be applied to the haul line to swing the bucket counter-clockwise from the position shown to the position shown in Figure 4 in which the teeth of the bucket point downwardly. The bucket is then in condition to be dropped with the teeth foremost into the material being excavated.

The application of tension to the haul line while the bucket is in the rearwardly tilted position of Figure 3 not only swings the bucket clockwise, but it causes the clevis members 18 to swing outwardly to approximately the position shown in Figure 1 as the bucket approaches the horizontal position. As the bucket swings beyond the horizontal position during such clockwise movement by the angular momentum imparted thereto by the haul line, the inclined axes of the members 18 cause them to move inwardly of the bucket and hence such forward rotation of the bucket is not arrested by the members 18 unless the operator improperly manipulates the haul line by maintaining too much tension thereon or takes the line in too slowly. When the

bucket is given suitable angular velocity as it approaches the horizontal position and the haul line is then suitably slackened, the bucket will continue its forward rotation to the position shown in Figure 4. As the stabilizer lines 22 become taut as the bucket approaches the forward position and the members 18 are thereby swung inwardly of the bucket to the dotted line position shown in Figure 4, in which position, it will be seen, they are disposed above the teeth, they do not prevent the teeth from penetrating the material as the bucket is lowered or dropped to initiate the next loading operation. When tension is again applied to the haul line during the loading operation, the clevis members 18 will be swung outwardly to the positions shown in Figure 1. Tension applied to the haul line during the loading operation, being applied to the bucket at positions above the teeth, tend to tilt the bucket forwardly to a proper digging angle. The action of the members 18 is in character a wrist action and since tilting of the bucket causes swinging movement of the members 18, conversely, swinging movement of those members outwardly or inwardly tends to cause the bucket to tilt rearwardly or forwardly, respectively.

The members 18 are secured to the bucket adjacent the vertical plane passing through the teeth, and hence it is at these positions of the bucket that the force of the haul lines is applied to the bucket. The members 18 are thus substitutes for the usual forwardly extending portions of the side walls of the bucket to which the haul lines generally are attached in present-day practice. Since by reason of the present arrangement the forces exerted on the drag bucket by the haul line during loading operations are applied to the relatively heavy side walls of the bucket at positions substantially to the rear of the positions at which haul lines are attached to conventional buckets having forwardly extending side walls, the present improvements result in a more durable bucket, other things being equal. It will also be observed that since the members 18 in effect constitute lever extensions of the side walls of the bucket which project a considerable distance forwardly of the axis 14-14, they enable rearward tilting of the loaded bucket to be resisted with less tension on the haul line than would be the case were the branches 20 connected to the bucket proper, and consequently the improved bucket can be elevated more nearly beneath the point of the boom of the drag line apparatus.

In the type of bucket illustrated in the drawing, the pivot pins 19 are disposed on angular axes that converge downwardly and are located in a transverse plane at or adjacent the forward portions of the teeth. In utilizing the present invention in buckets of the type illustrated, the axes of the pins preferably are disposed at angles to the vertical of from 25 degrees to 35 degrees. Improved action of the bucket results from canting the axes a few degrees rearwardly also from a vertical plane, as illustrated in the drawing. In other words the angular disposition of the pins 19 is such that when the bucket starts tilting rearwardly from its normal load carrying position illustrated in Fig. 6, the resultant of the force exerted on the members 18 by the haul line and the force of gravity on the members 18 causes them to swing outwardly and assume the positions shown in Figure 3.

The arrangement of the parts of the bucket illustrated is such that when the bottom of the

bucket and haul line are parallel, as illustrated in Figure 5, and in horizontal planes, a plane passed through the points of the teeth and the forward ends of the clevis members 18 is at an angle of approximately 40 degrees to the horizontal. The angle of that plane to the horizontal varies, however, as the angle of the haul line is varied with respect to the plane of the bottom of the bucket as will be seen.

It will be apparent that various changes may be made in the illustrative structure disclosed without departing from the spirit of the invention.

I claim:

1. In combination a drag bucket and a pair of rigid members adapted for attachment at the forward ends thereof to haul line branches and being hinged at the rear ends to forward portions of the bucket on downwardly convergent axes for causing said members and the attached ends of said branches to swing by gravity laterally of the bucket upon rearward tilting of the latter and the slackening of said branches.

2. In combination a drag bucket, haul line branches therefor, and means for securing said branches to the bucket comprising a pair of rigid members adapted to be attached at the forward ends thereof to said branches and being hinged at the rear ends thereof to forward portions of the bucket on downwardly convergent and rearwardly inclined axes, whereby said members tend to swing laterally of the bucket upon rearward tilting thereof.

3. Drag line apparatus comprising a drag bucket, means for attaching hoist line branches to the bucket on an axis whereby the bucket when normally loaded tends to tilt rearwardly to load discharging position, and means for attaching haul line branches to forward portions of the bucket whereby tension on the haul line can be utilized to resist rearward tilting action of the loaded bucket during elevation thereof, said means comprising a pair of forwardly extending members to the forward ends of which said haul line branches are adapted to be attached and being hinged at the rear ends thereof to forward portions of the bucket on downwardly convergent axes to cause the members to swing outwardly by gravity to move the adjacent ends of said haul line branches out of the path of movement of the forward portions of the tilting bucket upon release of tension of the haul line.

4. Excavating apparatus comprising a bucket having side walls, a rear wall, and a bottom having a forward cutting edge, hoist line attaching means for the bucket providing an axis so located that the bucket when loaded tends to tilt rearwardly for discharging the load over said rear wall, and means for attaching haul line branches to the forward end of the bucket comprising a pair of rigid members adapted to be attached at the forward ends thereof to said branches and being hinged at the rear ends to forward portions of said side walls on downwardly convergent axes whereby the forward ends of said members move outwardly upon rearward tilting of the bucket for moving said branches out of the path of movement of said cutting edge.

5. A rearwardly dumping drag bucket provided with means for attaching a hoist line thereto on an axis so located that the bucket when normally loaded tends to tilt rearwardly to load discharging position and whereby the elevated bucket when empty can hang pendent from the hoist line in either a forwardly or rearwardly tilted position, haul line attaching means at the forward end of the bucket comprising a pair of rigid members adapted to be attached at the forward ends thereof to haul line branches and hinged at the rear ends thereof to forward portions of the bucket on downwardly convergent axes to cause said members to swing outwardly of the bucket upon rearward tilting of the latter from load carrying toward load discharging position, and thereby move the connected ends of the haul line branches out of the arcuate path of movement of the forward portions of the tilting bucket, and lines connected to the forward ends of said members and to said hoist line branches and of such length as to swing the outer ends of said members inwardly with respect to the bucket and above the forward cutting edge thereof as said bucket is moved to the forwardly tilted pendent position whereby as the bucket is lowered in such pendent position the cutting edge thereof can be caused to contact the material to be excavated without obstruction by said pivoted members.
- 10 6. A drag bucket provided with haul line attaching members at the forward end thereof, and hinged means connecting said members to the bucket on downwardly convergent and rearwardly inclined axes for causing said members to swing outwardly and rearwardly of the bucket upon release of tension on said line and upon rearward tilting thereof from load carrying position to effect a rearward shifting of the center of gravity of the bucket to accelerate movement thereof to load discharging position.
- 15 7. A drag bucket provided with hoist members secured to the bucket on an axis so located that the bucket when loaded tends to tilt rearwardly to load discharging position, a pair of rigid members hingedly connected at the rear ends thereof to forward portions of the bucket, haul line branches connected to the forward ends of said members, and flexible stabilizing members connected to forward portions of said members and to said hoist lines at points above the bucket for restraining forward tilting of the loaded bucket when elevated and when tension is applied to the haul lines, the axes of said hinged connections being downwardly convergent and rearwardly inclined whereby upon release of tension on said haul lines while the loaded bucket is elevated said rigid members swing outwardly by gravity beyond the planes of the respective bucket side walls for swinging the adjacent portions of the 20 haul line branches and the stabilizing members out of the path of the forward portion of the bucket as the latter tilts to load discharging position and whereby the center of gravity of the bucket is shifted rearwardly and the angular velocity of the dumping movement of the bucket is thereby accelerated.
- 25 8. A rearwardly dumping drag bucket provided with means for attaching a hoist line thereto on an axis so located that the bucket when normally loaded tends to tilt rearwardly to load discharging position and whereby the elevated bucket when empty can hang pendent from the hoist line in either a forwardly or rearwardly tilted position, haul line attaching means at the forward end of the bucket comprising a pair of rigid members adapted to be attached at the forward ends thereof to haul line branches and hinged at the rear ends thereof to forward portions of the bucket on downwardly convergent axes to cause said members to swing outwardly of the bucket upon rearward tilting of the latter from load carrying toward load discharging position, and thereby move the connected ends of the haul line branches out of the arcuate path of movement of the forward portions of the tilting bucket, and lines connected to the forward ends of said members and to said hoist line branches and of such length as to swing the outer ends of said members inwardly with respect to the bucket and above the forward cutting edge thereof as said bucket is moved to the forwardly tilted pendent position whereby as the bucket is lowered in such pendent position the cutting edge thereof can be caused to contact the material to be excavated without obstruction by said pivoted members.
- 30 9. A drag bucket provided with haul line attaching members at the forward end thereof, and hinged means connecting said members to the bucket on downwardly convergent and rearwardly inclined axes for causing said members to swing outwardly and rearwardly of the bucket upon release of tension on said line and upon rearward tilting thereof from load carrying position to effect a rearward shifting of the center of gravity of the bucket to accelerate movement thereof to load discharging position.
- 35 10. A drag bucket provided with hoist members secured to the bucket on an axis so located that the bucket when loaded tends to tilt rearwardly to load discharging position, a pair of rigid members hingedly connected at the rear ends thereof to forward portions of the bucket, haul line branches connected to the forward ends of said members, and flexible stabilizing members connected to forward portions of said members and to said hoist lines at points above the bucket for restraining forward tilting of the loaded bucket when elevated and when tension is applied to the haul lines, the axes of said hinged connections being downwardly convergent and rearwardly inclined whereby upon release of tension on said haul lines while the loaded bucket is elevated said rigid members swing outwardly by gravity beyond the planes of the respective bucket side walls for swinging the adjacent portions of the 40 haul line branches and the stabilizing members out of the path of the forward portion of the bucket as the latter tilts to load discharging position and whereby the center of gravity of the bucket is shifted rearwardly and the angular velocity of the dumping movement of the bucket is thereby accelerated.
- 45 11. A rearwardly dumping drag bucket provided with means for attaching a hoist line thereto on an axis so located that the bucket when normally loaded tends to tilt rearwardly to load discharging position and whereby the elevated bucket when empty can hang pendent from the hoist line in either a forwardly or rearwardly tilted position, haul line attaching means at the forward end of the bucket comprising a pair of rigid members adapted to be attached at the forward ends thereof to haul line branches and hinged at the rear ends thereof to forward portions of the bucket on downwardly convergent axes to cause said members to swing outwardly of the bucket upon rearward tilting of the latter from load carrying toward load discharging position, and thereby move the connected ends of the haul line branches out of the arcuate path of movement of the forward portions of the tilting bucket, and lines connected to the forward ends of said members and to said hoist line branches and of such length as to swing the outer ends of said members inwardly with respect to the bucket and above the forward cutting edge thereof as said bucket is moved to the forwardly tilted pendent position whereby as the bucket is lowered in such pendent position the cutting edge thereof can be caused to contact the material to be excavated without obstruction by said pivoted members.
- 50 12. A rearwardly dumping drag bucket provided with means for attaching a hoist line thereto on an axis so located that the bucket when normally loaded tends to tilt rearwardly to load discharging position, a pair of rigid members hingedly connected at the rear ends thereof to forward portions of the bucket, haul line branches connected to the forward ends of said members, and flexible stabilizing members connected to forward portions of said members and to said hoist lines at points above the bucket for restraining forward tilting of the loaded bucket when elevated and when tension is applied to the haul lines, the axes of said hinged connections being downwardly convergent and rearwardly inclined whereby upon release of tension on said haul lines while the loaded bucket is elevated said rigid members swing outwardly by gravity beyond the planes of the respective bucket side walls for swinging the adjacent portions of the 55 haul line branches and the stabilizing members out of the path of the forward portion of the bucket as the latter tilts to load discharging position and whereby the center of gravity of the bucket is shifted rearwardly and the angular velocity of the dumping movement of the bucket is thereby accelerated.
- 60 13. A rearwardly dumping drag bucket provided with means for attaching a hoist line thereto on an axis so located that the bucket when normally loaded tends to tilt rearwardly to load discharging position and whereby the elevated bucket when empty can hang pendent from the hoist line in either a forwardly or rearwardly tilted position, haul line attaching means at the forward end of the bucket comprising a pair of rigid members adapted to be attached at the forward ends thereof to haul line branches and hinged at the rear ends thereof to forward portions of the bucket on downwardly convergent axes to cause said members to swing outwardly of the bucket upon rearward tilting of the latter from load carrying toward load discharging position, and thereby move the connected ends of the haul line branches out of the arcuate path of movement of the forward portions of the tilting bucket, and lines connected to the forward ends of said members and to said hoist line branches and of such length as to swing the outer ends of said members inwardly with respect to the bucket and above the forward cutting edge thereof as said bucket is moved to the forwardly tilted pendent position whereby as the bucket is lowered in such pendent position the cutting edge thereof can be caused to contact the material to be excavated without obstruction by said pivoted members.
- 65 14. A rearwardly dumping drag bucket provided with means for attaching a hoist line thereto on an axis so located that the bucket when normally loaded tends to tilt rearwardly to load discharging position and whereby the elevated bucket when empty can hang pendent from the hoist line in either a forwardly or rearwardly tilted position, haul line attaching means at the forward end of the bucket comprising a pair of rigid members adapted to be attached at the forward ends thereof to haul line branches and hinged at the rear ends thereof to forward portions of the bucket on downwardly convergent axes to cause said members to swing outwardly of the bucket upon rearward tilting of the latter from load carrying toward load discharging position, and thereby move the connected ends of the haul line branches out of the arcuate path of movement of the forward portions of the tilting bucket, and lines connected to the forward ends of said members and to said hoist line branches and of such length as to swing the outer ends of said members inwardly with respect to the bucket and above the forward cutting edge thereof as said bucket is moved to the forwardly tilted pendent position whereby as the bucket is lowered in such pendent position the cutting edge thereof can be caused to contact the material to be excavated without obstruction by said pivoted members.

RAYMOND S. WEIMER.
